UNITED STATES PATENT OFFICE.

THOMAS A. ROY, OF DORCHESTER, AND JOHN H. HINDLEY, OF MALDEN, MASSACHUSETTS, ASSIGNORS OF ONE-THIRD TO JAMES PRICE, OF MALDEN, MASSACHUSETTS.

FLEXIBLE TEMPLET.

1,078,879.

Specification of Letters Patent. Patented Nov. 18, 1913.

Application filed November 4, 1912. Serial No. 729,493.

To all whom it may concern:

Be it known that we, THOMAS A. ROY, a citizen of the Dominion of Canada, residing at Dorchester, in the county of Suffolk and 5 State of Massachusetts, and JOHN H. HINDLEY, residing at Malden, in the county of Middlesex and State of Massachusetts, have invented a new and useful Improvement in Flexible Templets, of which the following 10 is a specification.

Our invention relates to the tools used by wood workers, iron workers and draftsmen for laying out and duplicating various simple and compound curves.

15 Our objects are: First, to provide a tool or instrument capable of being set to any desired or existing curve, whether composed of portions of the arc of a circle or any other geometrical curve. Second, to provide means of fixing the curve so formed rigidly and positively. Third, to provide adjustable means for accurately locating said curve with reference to any straight line contiguous to it, or forming a part in 20 connection with it, in a manner similar to the use of the wood worker's "square" or his "bevel." We attain these objects by 25 the mechanism illustrated in the accompanying drawing, in which:

30 Figure 1 is a plan view of our flexible templet, arranged as a square; Fig. 2 is a similar view of a portion of the tool arranged as a bevel; Fig. 3 is an edge view showing the square attachment; and Fig. 4 is an edge view showing the connection of the flexible bar, and rigid bar by means of 35 the adjustable connecting bars.

Similar letters refer to similar parts in the several views.

40 The construction of our device is as follows:

A is a flexible bar of metal, preferably steel, to which is riveted a number, (in this case ten) of right angle pieces a a. Riveted 45 loosely or pivoted to these are the slotted adjusting bars B B. The bar C is rigid, preferably of steel, and has tapped into it the thumb screws c c, each of which passes through the slot of one of the adjusting bars B B 50 which may be secured in adjusted position on said bar C by the thumb screws c c. Geometrically considered the flexible bar A may form any kind of a curve, of which the bar C is the abscissa and the adjusting

bars B B are the ordinates. The rigid bar 55 C is slightly checked, or formed in fine ridges at right angles to each other as shown in Figs. 1 and 2, for the purpose of affording a firmer grip to the adjusting bars B B when set and fixed in any desired position. 60 The adjusting bar B at the end of the tool may be removed and the right angle piece D substituted. This, when set at right angles to the rigid bar C, forms a "square;" its downwardly projecting flange d, (Fig. 3) 65 being adapted to be placed against the edge of any straight portion of wood or metal to which the curve to be formed may be related.

In Figs. 1 and 2 the adjusting bars are 70 shown at nearly right angles to the rigid bar C. It is obvious, however, that the bars B B being pivoted, practically at both ends, may be placed in any angular position to the rigid bar C. This would place the 75 right angle piece D in the same angular position and thus form a "bevel" instead of a "square." A right angle piece similar to D may be used on the opposite end of the device by making the pivot hole for the 80 thumb screw c in the opposite end.

Fig. 2 shows the right angle piece D detached from the right angle piece a and placed under the rigid bar C, where it is secured by the thumb screw c and adjusted 85 to form a "bevel" while the adjusting bars B B remain at substantially right angles to the rigid bar C.

In using our device, say for fitting wood or metal parts to existing curved portions, 90 all the thumb screws c c on the rigid bar C are loosened, the rigid bar placed in the desired position, and the adjusting bars B B pushed out, one at a time, forcing the flexible bar A against the existing curved surface, and fastening them by the thumb screws c c. To render the curve accurate it 95 may be necessary to go through this operation more than once, but it is obvious that a very accurate curve may be thus formed, 100 and that when so formed may be rigidly maintained. For instance; in fitting flooring in curved corners or around the base of a column, or in similar places, not only 105 can an accurate counterpart of the existing curve be made, but by the use of the right angle piece D, set against the edge of the portion of floor already laid, and then ap-

plied in the same manner to the portion next to be laid, very quick and accurate fits can be made. Many other uses in both wood and iron work will readily suggest themselves to the practical mechanician.

We are aware that flexible curves, capable of adjustment, have been heretofore made for the use of draftsmen, but they are not of sufficient rigidity, when adjusted, to be useful to woodworkers or iron workers. There is no provision made for a "square" or "bevel" attachment whereby the curve to be made may be formed with reference to any straight edge or surface connected with it or related to it.

Our device fulfils these conditions and is

in actual, practical, and successful use for these purposes.

We therefore claim:

In a flexible templet, the combination of 20 a flexible bar, a rigid bar, a multiplicity of adjusting bars pivoted to said flexible bar and slidably attachable to said rigid bar, and a right angle bar adjustably connected to said rigid bar to form therewith a square 25 or a bevel substantially as described.

THOMAS A. ROY.
JOHN H. HINDLEY.
